HAIR COMB

Nicholas T. Baldanza, Rutherford, N. J., assignor
to Columbia Protektosite Company, Inc., Carl-
stadt, N. J., a corporation of New Jersey

Application September 5, 1946, Serial No. 694,907

2 Claims. (Cl. 132—11)

1

This invention relates to hair combs.

One object of the invention is to provide a comb having improved means for freely supporting the same on a plane surface in inverted position, with the comb teeth projecting upwardly whereby this article may be designated as a stand-up comb.

Combs of this character have the advantage of occupying very little space on the dressing table and of permitting rapid air-drying of the 10 comb teeth, and the comb affords an attractive display novelty on a lady's dressing table. According to the usual practice, combs are generally ornamented as by having decorative configurations at the back thereof, and I have perceived that the provision of a base or supporting means on the comb would materially interfere with the character and scope of the decoration that might be provided, as well as with the modes of manufacture employed.

It is therefore an object of the invention to provide a stand-up comb having improved means such that the comb support shall leave ample room for the provision of any desired decorative configuration at the back of the comb, without interfering with the scope of the design employed or with the method of manufacture utilized.

I have also perceived that the support portion of a stand-up comb tends to interfere with the normal holding of the comb at the back thereof so that various people find use of such a comb objectionable.

It is therefore another object of the invention to furnish a stand-up comb having improved means whereby the major section at the back of the comb may remain conventional or be otherwise formed relatively narrow to facilitate the holding in the hand of the operator while maintaining provision for ample stability of the comb in its inverted position with the comb teeth projecting upwardly.

Another object of the invention is to construct a stand-up comb having improved means for supporting the same and for locating the operator's hand over the comb or preventing accidental slippage of the comb from the hand.

Another object of the invention is the provision of a stand-up comb having improved supporting means so arranged and constructed that the back of the comb may have any desired contour and any required decorative material which might project from the main body of the back without interfering with a stable positioning of the comb on its supporting means.

Another object of the invention is the provision of a stand-up comb of the nature set forth adapted to be manufactured inexpensively as a one-piece construction and requiring comparatively little material and being light in weight, and generally regular, neat and compact in appearance, and adapted for convenient use in the usual manner in combing the hair.

2

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in side elevation with parts removed and indicated in dot-dash lines showing a stand-up comb embodying the invention, in its inverted position and with its teeth projecting upwardly as contemplated by the invention.

Fig. 2 is a bottom plan view thereof.

Fig. 3 is a sectional view on the line 3—3 of Fig. 1.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes as a new article of manufacture, a hair comb 35 of a particular novel construction so that it is best designated as a stand-up comb. The same includes a relatively straight row of teeth 11 comprising the end guard teeth 12 integrally connected to a backing member 13. Attached to or 40 integral with the back 13 is a base 14 at an edge of the backing member opposite that at which the comb teeth are disposed. The base 14 provides a relatively flat seating surface 15 which may be slightly concave so that any protrusion formed at the parting line of the mold will be immaterial. This seating surface 15 extends partially along the length of the comb and its transverse dimension is substantially greater than that of the backing member 13 to afford 45 stability for the comb when the latter is freely resting on any plane surface or table in inverted position and with its teeth projecting upwardly. This seat 15 lies in a plane approximately at right angles to the row of teeth 11 and 12 and is arranged in generally symmetrical relation 50 thereto so as to afford suitable positioning of the comb and it is substantially wider or greater in transverse dimension for this purpose than the main body of the back 13 at least at the edge thereof to which the comb teeth are connected.

Preferably there is provided a widened portion 55 16 to form the seat 15. This portion 16 is sub-

stantially less in length than the back 13 or is interrupted to provide a plurality of rest portions specifically shown at 16, whose total length is substantially less than that of the back. These portions 16 may be located at various points along the back 13, and are preferably positioned at or adjacent to the ends thereof. Accordingly it will be perceived that a reference to "end portions 16" is not intended to be limiting to extreme end positions. According to the principle defined there are thus formed one or more major portions on the back 13 which are free of the widened portions 16, and preferably there is a single intermediate portion 17 of the back which is relatively narrow or substantially less in transverse dimension than the portion 16. This intermediate section is intended to have such width as is normally used in a conventional comb for the purpose of affording a back of sufficient strength and rigidity for properly mounting the comb teeth. Further, it will be noted that this intermediate section 17 is such as will afford a neat and convenient hand-hold for the operator. Accordingly, the portion 17 may have any required ornamentation or configuration at its free edge 18. In other words, the back of the comb may have any desired molded decorative characteristics which may be formed along one or both of the side faces thereof and continue to or around the free edge 18 without interruption to produce a continuous attractive design. In order that such a decorative configuration shall not interfere with the use of the seating surface 15, the portions 16 project behind the free edge 18, whereby the comb may be properly positioned in its inverted form on a table or the like having a cloth covering provided with an embroidered or other irregular surface, and the design itself may be produced according to varying dimensions and without limitation by reason of the stand-up character of the comb. In an illustrative sense only, the design may comprise a plurality of longitudinal ribs 19, but such ribs may also be transverse to the free edge 18.

The portions 16 also serve as a hand positioning means and when located in spaced relation to each other, they provide confronting shoulders 20, these shoulders tapering to a maximum adjacent to the free edge 18. Being formed on opposite sides of the comb, these shoulders 20 are sufficient to prevent the comb from accidentally slipping out of the hand of the operator holding the back 17 in the usual manner, even though the sections 16 may project only slightly behind the free edge 18 to provide a neat configuration for the comb as a whole. The sections 16 may taper toward the inner edge 21 so as to fade out and the side faces may be slightly concave.

The comb 10 is desirably formed as a one-piece article, of plastic or other suitable material by molding or any other feasible process.

It is thus seen that the comb 10 includes a back having end portions 16 sufficiently widened and having flat faces 15 to provide a suitable and reliable support in freely resting the comb in an inverted position with the comb teeth projecting upwardly. Between these end portions there is an intermediate relatively narrow portion 17 which is convenient as a hand-hold and is adapted to have any required decorative configuration. The end portions 16 may be regarded as constituting integral pedestals or protrusions, lateral or otherwise, and they may also project slightly behind the free edge 18 of the intermediate portion to clear the decorative configuration. These por-

tions 16 may be sufficiently small so that the comb preserves its essential character and appearance without introducing any freakishness. It provides shoulders as at 20 for locating the hand of the operator and for preventing the comb from accidentally slipping from the hand. The comb thus illustrates the provision of a back having at its free edge supporting means substantially less in length than the back, interrupted to form sections spaced from the center of the comb at which the decorative configuration is generally located. Such a comb occupies little space on a dressing table and is adapted to quickly air dry if wet and can be conveniently held and manipulated without obstruction by the supporting portions.

I claim:

1. As a new article of manufacture, a one-piece comb having a back carrying a relatively straight row of teeth at one edge thereof, integrally formed rest portions spaced apart on the other edge of said back adjacent the ends thereof, said back having an intermediate portion therebetween of uniformly thinner cross section from edge to edge than said end portions, the said end portions having relatively flat faces lying in a plane approximately at right angles to the axes of said comb teeth, the width of said faces corresponding to the thickness of said end portions thereat being substantially greater than the thickness of said intermediate portion to provide areas constituting a seat for freely supporting the comb in a stable manner thereon with the teeth projecting upwardly, said end portions tapering toward the edge of the back from which the teeth extend, said intermediate portion being positioned in a clearing setback relation with respect to said plane extending through said seat.

2. As a new article of manufacture, a one-piece comb having a back carrying a relatively straight row of teeth at one edge thereof, integrally formed rest portions spaced apart on the other edge of said back adjacent the ends thereof, said back having an intermediate portion therebetween of uniformly thinner cross section from edge to edge than said end portions, the said end portions having relatively flat faces lying in a plane approximately at right angles to the axes of said comb teeth, the width of said faces corresponding to the thickness of said end portions thereat being substantially greater than the thickness of the intermediate portion to provide areas constituting a seat for freely supporting the comb in a stable manner thereon with the teeth projecting upwardly, said end portions tapering toward the edge of the back from which the teeth extend, said intermediate portion being positioned in a clearing setback relation with respect to said plane extending through said seat, and confronting shoulders provided on said spaced apart rest portions to serve as hand locating means and to prevent accidental slippage from hand grip thereon.

NICHOLAS T. BALDANZA.
